UNITED STATES PATENT OFFICE.

M. DE CAMP, OF SOUTH BEND, INDIANA.

MILLSTONE-BUSH.

Specification of Letters Patent No. 24,106, dated May 24, 1859.

To all whom it may concern:

Be it known that I, M. DE CAMP, of South Bend, in the county of St. Joseph and State of Indiana, have invented a new and Improved Millstone-Bush; and I do hereby declare that the following is a full, clear, and exact description of the same, reference being had to the annexed drawings, making a part of this specification, in which—

10 Figure 1, is a vertical section of my invention taken in the line x, x , Fig. 2. Fig. 2, is a horizontal section of the same, taken in the line y, y , Fig. 1.

Similar letters of reference indicate corresponding parts in the two figures.

The object of this invention is to obtain a durable bush for the spindle of the bed stone, one that will admit of a certain degree of adjustability so as to conform in itself 20 to the position of the spindle and be self-adjusting to a certain extent, one that will also insure a perfect lubrication of the spindle and admit of an easy adjustment of the followers to the collar of the same, and 25 also protect the spindle from foreign substances that might otherwise work between the collar and followers and produce unnecessary friction and wear.

To enable those skilled in the art to fully 30 understand and construct my invention I will proceed to describe it.

A, represents a rectangular metal box, which is fitted in the eye of the bed stone and secured therein by any proper means. 35 This box has a tubular vertical projection B, at its center through which the spindle C, passes and in which it is allowed to rotate freely. On the spindle C, a collar D, is secured. This collar is cylindrical, is also 40 hollow and fits loosely over the central tube B, of the box A, as shown clearly in Fig. 1. The lower edge of the collar D, is rounded or beveled at its inner side as shown at a . On the top of the box A, and between it and 45 a cover E, a piece of leather or other suitable packing b , is placed, the cover E, being secured to the box A, by screws c . The collar D, extends upward through the center of the cover E, and it is encompassed by an annular flanch d , on the cover E, the flanch and collar being covered by a plate F, which 50 is placed on a polygon d' , on the spindle C.

Within the box A, four vertical plates e , are placed, said plates being fitted between 55 projections f , on the inner sides of the box and resting on ledges g , on the inner sides

of the box a short distance above its bottom. To the inner side of each plate e , two vertical and parallel guides h, h , are placed which receive the followers F. These followers 60 may be of Babbitt or other similar metal and their inner surfaces are concave corresponding inversely to the surface of the collar D, as shown clearly in Fig. 2. The backs of the followers F, as well as their 65 sides are made of convex form, as shown clearly in Fig. 1. Through each plate e , a screw i , passes horizontally and bears against the backs of the followers. Each screw i , has a serrated or toothed wheel i' , 70 on its outer end into which stops j , catch, said stops being attached to plates k , which fit in the top of the box and behind the plates e , see Fig. 1.

The box A, is supplied with oil which as 75 the spindle C, rotates, lubricates the followers F, and collar D, the oil passing up between the followers and the collar. The oil is prevented from passing up between the tube B, and collar D, on account of 80 the inner sides of the collar at its bottom being rounded, and also by the space between the tube and collar being too great to permit the oil to ascend freely. The followers F, are adjusted to the collar D, by 85 removing the plate k , and turning the wheels i' , of the screws i , the stops j , of the plate k , preventing the wheels i' , from 90 casually turning. On account of having the followers F, of convex form they are allowed to adjust themselves to the spindle in case the latter is out of line. All heating 95 of the spindle is thereby avoided.

The box A, may be of cast metal, the spindle C, of course being of wrought metal 95 with a properly turned collar.

I do not claim broadly the employment or use of a hollow collar D, encompassing a tube B, in a box A, for such device has been previously used, but I am not aware that 100 followers provided with convex sides have been used in connection with a collar D, to permit the followers to conform to the position of the spindle in the event of the latter being out of line. Neither am I aware that 105 regulating or adjusting screws i , have been employed with serrated wheels i' , at their ends and used in connection with stops j , to prevent the casual turning of the screws and the consequent misplacement of the followers. I do not claim therefore broadly, 110 irrespective of construction and arrange-

ment the employment or use of adjustable followers. Neither do I claim adjusting screws *i*, in themselves considered; but,

I do claim as new and desire to secure by
5 Letters Patent,

1. The adjustable followers *F*, provided
with convex sides and backs fitted within
an oil box *A*, and arranged in relation with
the collar *D*, of the spindle to operate as
10 and for the purpose set forth.

2. The serrated or notched wheels *i*, at-
tached to the outer ends of the screws *i*,
when used in connection with the stops *j*,
attached to the plates *k*, substantially as
and for the purpose specified.

M. DE CAMP.
